UNITED STATES PATENT OFFICE

2,515,826

ADJUSTABLE TRUNK CARRIER

Clarence Hall, Omaha, Nebr.

Application April 7, 1947, Serial No. 739,807

1 Claim. (Cl. 224—45)

1

This invention relates to an improvement in trunk carriers and has for its object the provision of a convenient device for carrying trunks up and down inclined ramps and stairways.

A further object of the invention is to provide a trunk carrying device provided with suitable outwardly projecting carrying handles.

Another object of the invention is to provide a trunk carrier having a frame for supporting a trunk thereon, the frame being so constructed as to be readily extensible and retractible for receiving trunks of various sizes.

Still another object of the invention is to provide an adjustable trunk carrying frame the parts of which may be rapidly locked together for use and unlocked for adjustment.

A still further object of the invention is to provide a trunk carrier as described having adjustable straps secured thereto for maintaining a trunk thereon at times when the latter is being carried at an inclination.

Yet another object of the invention is to provide a trunk carrier as described having telescopically disposed frame members, at least one of the frame members having a slot therein extending substantially completely the whole length thereof for providing the device with a maximum length when extended and at times when the slotted frame member is secured to its complementary telescopic frame member.

Other and still further objects and advantages of the invention will become apparent from the following detailed description of a preferred embodiment thereof.

In the drawings:

Figure 1 is a top plan view of the trunk carrier of the invention shown in a position of use upon a trunk, the latter being shown in dotted lines;

Figure 2 is a side elevation of the trunk carrier and trunk of Figure 1;

Figure 3 is an end view of the trunk carrier of Figure 1, the view being taken by turning the device through an angle of ninety degrees from the position thereof shown in Figure 2; and

Figure 4 is a detailed side elevation of the locking device of the invention which includes two of the telescopically cooperative frame members of the new carrier.

The trunk carrier of this invention is for the purpose of carrying a trunk of relatively great size and bulk, such a trunk being indicated at 10 in Figure 1.

The new device includes a pair of oppositely disposed, rigid, parallel, elongated transverse frame members 12. The transverse frame mem-

bers 12 are preferably formed of angle iron, the outwardly disposed sides of the angle irons being disposed upwardly extending in vertical planes from the normally horizontally disposed remaining portion of the angle iron 12.

The angle irons 12 are normally horizontally positioned and are provided with outwardly extending handles 14 firmly attached thereto. The handles 14 are preferably of U-shape in top plan view, the ends of the arms 16 of each of the handles 14 being welded or otherwise suitably secured to the frame members 12.

A plurality of longitudinal frame members 20 are provided. The latter are spaced apart, preferably equidistantly, and are each disposed at a right angle with respect to the parallel transverse frame members 12. Each of the longitudinal frame members 20 is composed of two sections 22 and 24.

20 The sections 22 are annular in cross section and may be formed of common pipes if desired. The latter are welded at their ends to one of the transverse frame members 12 so as to be rigidly disposed extending outwardly therefrom at a right angle. The sections 24 may optionally be formed of tubular construction and are similarly welded to their adjacent transverse frame member 12. The inner diameter of the pipes or frame members 22 is of a slightly larger diameter than the outer diameter of the sections 24 for slidably receiving the latter. As thus described, the longitudinal frame members 20 and the horizontal frame members 12 form a trunk carrying frame.

35 As best shown in Figure 4, one of the sections 22 of one of the frame members 20 is provided with a slot 30 longitudinally disposed in a side thereof, the slot 30 extending to a point 32 spaced from the inward or open end of the corresponding sections 22. A portion 34 of the said one section 22 is disposed between the adjacent end of the slot 30 and the open end of the pipe section 22. The section 34 is for the purpose of preventing a bolt or detent 36 from sliding outwardly of the slot 30.

40 The bolt 36 is provided with a head disposed on the outward side of the pipe 22 and of the slot 30, a shank disposed through the slot 30, and the threaded end portion threadedly and rigidly secured in the side wall of the frame section 24 corresponding with the slotted frame section 22 and adjacent the inward end of said frame member 24.

45 The purpose of the detent bolt 36 and the slot 30 is to provide a means for securing together

the two sections of the frame, one of such frame sections including the members 22 and that transverse frame member 12 to which they are attached, the other section including the members 24 and that frame member 12 to which the latter are attached.

A pair of straps 40 are provided. The latter are adapted to be disposed in parallelism extending across the top of the trunk 10 to be carried. The opposite ends of each strap 40 are secured by means of suitable rivets 42 to the oppositely disposed transverse frame members 12.

The straps 40 are each composed of two adjustably connected sections. One of the sections is provided with a series of spaced apart apertures 49 therein for the reception of the tongue 50 of a strap buckle 52. The other strap section 40 is looped about the belt buckle 52 as shown at 54; and a suitable sliding keeper 56 is provided for extending about the free end of the apertured strap section and the other strap section.

In place of the straps 40 any suitable, flexible, and adjustable device may be employed. Also the straps 40 may be caused to extend entirely around the lower side of the frame member 12; or may, if desired, be placed extending transversely rather than longitudinally about the frame.

In operation, it will be seen that the operator may adjust the sides of the frame by spacing the transverse frame members 12 a greater or lesser distance apart as may be desired. He may then place the trunk 10 upon the frame at a time when the straps 40 are unbuckled and disposed out of the way. The straps 40 are then tightened securely about the trunk 10 and buckled and the handles may then be gripped for carrying the trunk. The straps 40, if tightly adjusted, will prevent the frame members 22 and 24 from sliding farther apart, although, if desired, the bolt 36 may be tightened to maintain the frame sections 22 rigidly disposed in a desired position with respect to each other.

The bolt 36 and the slot 30 will cooperate to prevent the complete separation of the sections 22 and 24 even at times when the bolt 36 is not tightened against the adjacent side of the pipe 22.

This invention has provided a trunk carrier which is readily extensible for accommodating trunks of various sizes, to which a trunk may be

rapidly attached and from which a trunk may be readily removed.

From the foregoing description it is thought to be obvious that an adjustable trunk carrier constructed in accordance with my invention is particularly well adapted for use by reason of the convenience and facility with which it may be assembled and operated, and it will also be obvious that my invention is susceptible of some change and modification, including variations in the shape and size of the parts, without departing from the principles and spirit thereof and for this reason I do not wish to be understood as limiting myself to the precise arrangement and formation of the several parts herein shown in carrying out my invention in practice, except as claimed.

I claim:

A trunk carrier comprising a plurality of elongated parallel spaced apart longitudinal frame members, said frame members each having two sections, the sections of each of said frame members being telescopically disposed with respect to each other, corresponding sections of each of said frame members being secured together, one of said longitudinal frame members having a slot extending longitudinally of one of the sections thereof; carrying handles secured to said sections and a bolt threadedly secured to the other section of said one frame member and adapted to be tightened against said slotted frame member for securing said sections of said one of said longitudinal frame members together in any one of a plurality of positions with respect to each other.

CLARENCE HALL.
